UNITED STATES PATENT OFFICE.

KARL L. HERRMANN, OF DETROIT, MICHIGAN, ASSIGNOR TO THE STUDEBAKER CORPORATION, OF SOUTH BEND, INDIANA, A CORPORATION OF NEW JERSEY.

MACHINE FOR CUTTING PATCHES AND THE LIKE.

Application filed April 14, 1924. Serial No. 706,432.

This invention relates to machines particularly adaptable for use in connection with preparing leather or like material for patching, and for preparing patches for such material. Throughout the following description and claims when reference is made to leather, it will be understood that leather or any other pliable sheet material that may be used in a manner similar to that for which leather is used is included in the term.

In patching of leather or similar material it has been found that if the hole, depression or the like to be patched is prepared so that the material forming its limits, or side walls in the case of a hole, is formed to provide a relatively large area in respect to the hole, as by forming widely diverged side walls, and a patch corresponding in size and shape to the hole or depression so prepared is properly glued therein, the patched portion of the leather is just as strong as the unpatched portion, and it may be finished off so that for most practical purposes it is impossible to detect the patched portion. The difficulty heretofore has been that such patching has been a hand job, the hole in the leather being prepared by a knife in the hand of a workman and the patch therefore also being so prepared. The inevitable result is that such a hand method consumes a relatively long time and each patch must be fitted separately to each hole as it is practically impossible for a person to consistently manually form such a hole or patch to a predetermined shape and size.

It is an object of the present invention to provide a machine whereby a hole of predetermined size and shape may be formed in leather and a patch of predetermined size and shape which may correspond with the hole to be covered, may be formed from leather, thereby eliminating to a great extent the human element entering into the preparing of holes to be patched and patches therefor.

I have found in experimenting with this class of work that if a knife is drawn through the leather in one direction only, in an effort to obtain a hole or patch of the desired shape and size, that as soon as the knife passes the center line of the hole or patch, from which point the leather being removed is diminishing in thickness there is a tendency for the knife to dig or gouge into the leather, and consequently it

is almost impossible to obtain the same uniform reduction in thickness of the leather being removed from the last side cut as is obtained on the first side, with the result that an unsatisfactory hole or patch is formed. This is also true to a certain extent where the knife is drawn to the center of the hole or patch from two or three different directions.

Another object of the present invention is, therefore, to provide a machine for forming such holes in, or patches from leather wherein the knife blade removing the leather begins to cut uniformly around the perimeter of the hole or patch and is gradually and uniformly drawn in to the center thereof.

Another object is to provide a machine for cutting leather in which the path that the cutting edge of the knife is constrained to travel in is a spiral.

Still another object of the present invention is to provide a machine by the use of which a variety of predetermined sizes and shapes of holes may be formed in, or patches formed from, leather, the only changes being necessary in the machine when it is used for one shape or sized hole or patch to adapt it to cut a different sized hole or patch, are the substitution of easily demountable parts or in some cases merely a simple adjustment of the machine itself.

These being among the objects of the present invention, the same consists of certain features of construction and combination of parts to be hereinafter described, with reference to the accompanying drawings which illustrate a suitable embodiment thereof, and then claimed, having the above and other objects in view.

In the accompanying drawings like numerals refer to like parts throughout the several views, in which,

Figure 1 is a partially broken side view illustrating a machine incorporating therein a suitable embodiment of my present invention.

Figure 2 is a bottom plan view of the cutting head of the machine shown in Figure 1.

Figure 3 is a view of the above mentioned cutting head taken on the line 3-3 of Figure 1.

Figure 4 is a partially broken and sectioned fragmentary side view taken on the line 4-4 of Figure 3, showing the manner in which the leather is supported for cut-

ting, and certain parts of the machine in relation thereto.

Figure 5 is a perspective view of the cutter supporting member.

5 Figure 6 is a sectional view of one form of patch of the type which I obtain by the use of the machine illustrated taken perpendicular to the plane of the patch and through its center.

10 Figure 7 is a section of a piece of leather taken through the center of a hole of the type prepared for patching by the machine illustrated, perpendicular to the plane of the leather.

15 Although I use the term hole throughout the description of the invention, it is to be understood that the same refers to either an opening in the material or a depression therein, and I wish it to be understood that 20 I refer to any opening, depression, or "thin spot" in the material which it is to strengthen or patch.

The machine consists of a flat base 10 provided with an upwardly extending boss 11 into which is vertically threaded the post 12. The post 12 pivotally supports the swinging frame 13, the outer end of which carries the cutting head of the machine. The frame 13 is vertically adjustable on the post 12 by the nut 14 threadably engaging the post 12 below the frame 13. Projecting from the rear of the frame 13 is a boss 15 which is provided with a vertical opening for the locking plunger 16 which is rotatably and slidably received therein. An opening 17 in the boss 11 is adapted to receive the lower end of the plunger 16 and thereby lock the frame 13 in cutting position and prevent its swinging when in such position. The plunger 16 is normally kept in raised or unlocked position of the frame 13 by means of a coil spring 18 positioned in a partly compressed state about the plunger 16 between its head and the boss 15. In order to hold the plunger 16 in engagement with the opening 17, a projecting pin 19 is secured to the plunger 16 adjacent its lower end and is adapted to be engaged by the hook 20 secured to the boss 11 when the plunger 16 is depressed and rotated so as to bring the pin 19 under the hook 20, thus preventing the spring 18 from raising the plunger 16.

55 The outer end of the swinging frame 13 is provided with two vertically aligned bearings 21 and 22, and secured to the lower face of the frame 13 adjacent and concentric to the bearing 22 and in a plane perpendicular to the axis of the bearings 21 and 22, is the track plate 23. A vertically extending spindle 24 is journaled in the bearings 21 and 22 and projects through the track plate 23 and has formed at its lower end the cutter driving member 25. The spindle 24 also projects above the frame 13 and receives there-

on a driving element 26 which serves to furnish means for rotating the spindle 24, and the nut 27 which serves to hold the spindle 24 and member 25 from axial movement in relation to the frame 13 in a conventional manner. The cutter driving member 25 has formed therewith two horizontally extending arms 28 and 29 which support the cutter supporting member 30

The cutter supporting member 30 is pivotally secured in a horizontal plane to the arm 28 by a sunken head screw 31 upon which a nut 32 is threaded to hold the members in proper relative position. The opposite end of the cutter supporting member 30 is slidably supported by the screw 33 and nut 34 in the arcuate slot 35 formed in the arm 29, the slot 35 being formed in an arc about the center of the screw 31 to allow the cutter supporting member 30 to pivot about the screw 31 within the limits of the slot 35. As most clearly shown in Figures 4 and 5, the cutter supporting member 30 has a cutter seat 36 midway its length, or better stated, equally disposed either side of the axis of the spindle 24. The cutter seat 36 is at a slight angle to the horizontal plane of the supporting member and receives thereon a cutting blade or cutter 37, which is clamped thereto by the clamping member 38 overlying it and which draws it down against the seat 36 by means of the screw 39 which passes through the seat 36 from below, through the cutter 37 and which threadably engages the clamping member 38, leaving the edge of cutter 37 projecting out towards the axis of the shaft 24 a predetermined amount.

In the lower face of the track plate 23 is formed a spiral groove or cam track 40 whose center is coincident with the axis of the spindle 24, and a guide or cam finger 41 is secured to the cutter supporting member 30 and projects upwardly therefrom and is received in the groove or cam track 40. Inasmuch as the screw 31, about which the cutter supporting member 30 is pivoted, is a fixed point relative to the axis of the spindle 24, it is readily apparent that the guide 41 co-operating with the track 40 controls the position of the cutter 37 in relation to the axis of the spindle 24, and it is further apparent that when the driving element or handle 26 is rotated, thereby turning the spindle 24, cutter driving member 25 and arms 28 and 29, the cutter supporting member 30 and its co-operating parts are caused to turn, and being pivoted about the screw 31 and being controlled by the guide 41 in track 40, the cutter is either brought towards or away from the axis of the spindle 24 by such turning movement. In other words, turning of the handle 26 causes the cutter 37 to turn about the axis of the spindle 24 and at the same time causes it to approach or to recede from the axis of the spindle 24 de-

pendent upon the shape of the cam track 41 and upon the direction of rotation of the spindle 24. It is also apparent that any movement of the cutter 37 due to turning the handle 26 is limited to a horizontal plane.

An upwardly projecting boss 42 in the shape of a frustrated cone is formed on the base 10, the axis of the boss 42 being at the same distance from the axis of the post 12 as is the axis of the spindle 24 and is concentric with the axis of the spindle 24 when the frame 13 is in locked or cutting position. Surrounding the boss 42 is a member 43 provided with an internal conical seat 15 to match the outside walls of the boss 41, the purpose of which will presently be described.

Concentric with the boss 42 and seated upon its upper surface is a removable button 44 which has a downwardly extending threaded projection 45 positioned in a central opening 46 in the upper surface of the boss 42 and which is seated against the boss 42 by the washer 47 and nut 48. The upper surface of the button 44 is shaped to the exact shape of the depression or side walls of the hole which it is desired to form in the leather to be cut, which shape is the same as that of the patch to be inserted in the hole so prepared.

In order to hold the guide or cam 41 against one side of the groove or cam track 40, and to prevent the same from sticking when the cutter 37 has traveled to its extreme inward position, a projecting arm 52 is secured to the cutter driving arm 29 and a coil spring 53 connects the hooked outer end of the same to the guide 41.

Having completed the description of the elements of the machine, the operation of the same will now be described. To illustrate the purpose and operation of the invention, I have shown a piece of leather 49 which has a hole 50 therein, such as a grub or other hole frequently found in leather, which it is desired to prepare for receiving a patch.

The handle 26 will first be turned so as to bring the cutter to the center of the button 44, and then the nut 14 will be adjusted to bring the cutting edge of the cutter down to a point substantially flush with the upper surface of the button 44. The handle 26 will then be turned to bring the cutter to its extreme position away from the center of the button 44. The plunger 16 will then be turned so as to bring the pin 19 from below the hook 20 which will raise the plunger 16 and allow the frame 13 to be swung away from the button 44. The piece of leather 49 will then be placed over the button 44 and member 42, with the center of the hole 50 approximately concentric with the center of the button 44. A ring 51 of proper internal diameter will then be

placed over the leather 50 and be forced down about the member 42, drawing the leather down tightly about the button 44 and member 42. The frame 13 and cutting head will then be swung back over the button 44, care being taken that the cutter 37 is in the proper position so as not to interfere with the leather 49, and the plunger 16 will then be depressed and locked in such position, securing the frame 13 from pivotal movement. The handle 26 will then be turned to bring the cutter 37 towards the center of the button 44, the cutting edge being drawn edgewise and inwardly at the same time. It is evident that as the cutter turns about, and at the same time approaches the center of the button 44, it begins to cut the leather 49 completely around the perimeter of the hole to be prepared, as indicated at 54, and the path of the cutting edge is 55 always around and towards the center of the button 44 during the whole cutting operation, no cutting whatever being done when the cutter 37 is moving away from the center of the button 44. When the cutting edge of the cutter 37 reaches the center of the button 44, the leather to be removed is completely severed and the direction of rotation of the handle 26 is then reversed and the cutter again brought to its extreme 56 outward position, the plunger 16 is released, the frame 13 and cutting head swung out of the way, the ring 51 is removed and then the leather 50 is removed, the hole 51 being now formed to the shape indicated in Figure 7 when the leather 50 is placed in flat position. Should another piece of leather with no hole in it be placed over the button 44 and the operations above described be repeated, it is evident that the leather removed 57 will form a perfect patch of the form shown in Figure 6 for the hole prepared by the previous operation.

It is evident that by changing the shape of the button 44, any desired shape or size of hole or patch may be obtained, and it is also practical to form merely a depression in the leather and to patch it when the damaged part of the leather to be patched does not extend clear through the thickness thereof.

It is further evident, and this is a particularly valuable feature in connection with this machine, that holes may be prepared and patches formed to a predetermined size as described, entirely independent of and apart from each other with resulting certainty that when a corresponding patch is eventually placed in a hole corresponding to it, the two will match perfectly. This feature will be seen to be of great value inasmuch as it does not necessitate each patch to be separately fitted to its respective hole.

Although I have shown in the machine illustrated in the drawings a specific form of cam plate, driving mechanism and other fea-

tures, I do not limit myself to these specific features as it is evident that the cam plate may be changed to obtain any other movement of the cutter desired, and that it is 5 within the knowledge of any good workman to change the machine so as to be power driven or to effect a variety of different movements and results as required by various conditions, without departing from the 10 spirit and substance of the broad invention, the scope of which is commensurate with the appended claims.

What I claim is:—

1. In a machine for removing a portion of 15 a piece of leather to thereby form a tapered seat in said leather, a leather supporting member, a knife blade rotatable about an axis, said knife blade being positioned at an incline with respect to said supporting 20 member during the cutting operation, and means dependent upon said rotation for varying the relative position of the knife with respect to said axis whereby to form a tapered seat in said leather.
2. In a machine for removing a portion of 25 a piece of leather to thereby form a tapered seat in said leather, a leather supporting member, a cutting element, said cutting element being positioned at an incline with respect to said supporting member during 30 the cutting operation, and means for causing said cutting element to move in a spiral path to thereby form a tapered seat in said leather.
3. In a machine of the class described, a 35 driving spindle provided with a laterally extending portion, a cutter carrying member pivoted to said extending portion in a plane perpendicular to said spindle, and means for controlling the relative position of said cutter carrying member in respect to the axis of said spindle.
4. In a machine of the class described, a 45 rotatable driving spindle provided with a laterally extending portion, a cutter carrying member pivoted to said extending portion in a plane perpendicular to the axis of said spindle, a cutter carried by said cutter carrying member, and means co-acting with said cutter carrying member for variably controlling 50 its relative pivotal position.
5. In a machine of the class described, a rotatable driving spindle provided with two 55 laterally extending portions, a cutter carrying member pivoted to one of said extending portions in a plane perpendicular to the axis of said spindle and slidably supported in the other of said extending portions, and means co-acting with said cutter carrying member for variably controlling its pivotal position.
6. In a machine of the class described, a 65 rotatable driving spindle provided with a laterally extending arm, a member carrying a cutter pivoted to said arm in a plane per-

pendicular to the axis of said spindle, means for rotating said spindle and means whereby said rotation will control the pivotal position of said member relative to said arm.

7. In a machine of the class described, a 70 rotatable spindle provided with means for movably supporting a cutter in a plane perpendicular to the axis of said spindle, means for rotating said spindle, and means whereby said rotation will control the rotative 75 and transverse positions of said cutter.

8. In a machine of the class described, a rotatable spindle provided with a laterally extending arm, a member pivoted to said arm in a plane perpendicular to the axis of 80 said spindle, and means whereby rotation of said spindle will cause said member to turn about said axis and vary its radial position in relation thereto.

9. In a machine of the class described, a 85 rotatable spindle provided with means for pivotally supporting a member about a line parallel and eccentric to the axis of said spindle, a relatively stationary member having a cam track in a plane perpendicular to the axis of said spindle, and means on said member for co-acting with said cam track.

10. In a machine of the class described, a rotatable spindle provided with a laterally extending arm, a cutter supporting member pivoted to said arm in a plane perpendicular to the axis of said spindle, a relatively stationary member provided with a cam track in a plane parallel to the pivotal plane of said cutter supporting member, and a member secured to said cutter supporting member co-acting with said cam track to vary the pivotal position of said cutter supporting member.

11. In a machine of the class described, a 105 rotatable spindle provided with a laterally extending arm, a cutter supporting member pivoted to said arm eccentric from the axis of said spindle, a relative stationary member provided with a cam track in a plane 110 perpendicular to the axis of said spindle, and a member on said first-named member engaging said cam track whereby when said second member is turned about the axis of said spindle its position in relation thereto 115 will be variably controlled.

12. In a machine of the class described, a stationary base supporting a pivotally mounted frame; a spindle rotatably mounted in said frame provided with a laterally extending arm pivotally supporting a cutter carrying member in a plane perpendicular to the axis of said spindle; a relatively stationary member secured to said frame; and means co-acting with said members for 120 variably controlling the position of the first mentioned member in respect to said axis.

13. In a machine of the class described, a stationary base supporting a pivotally mounted frame; means for adjusting said 130

frame in axial relation to its line of pivot; a spindle rotatably mounted in said frame; means for rotating said spindle; a cutting head supported by said spindle; a cutter secured to said cutting head; and means for causing movement of said cutter about the axis of said spindle and for varying its relative position in relation to said axis.

14. In a machine of the class described, 10 a stationary base supporting a swinging frame; means for locking said frame in a predetermined position; a spindle journaled in said frame; a cutter carrying member eccentrically pivoted to said spindle and rotatable therewith; a member provided with a cam track non-rotatably secured to said frame; and a cam on said member engaging said cam track whereby rotation of said spindle will vary the distance between said 20 member and the axis of said spindle.

15. In a machine for removing a portion of a piece of leather, a knife blade constrained to move in a spiral path; a leather supporting member provided with a surface 25 conforming in shape to the shape of said portion to be removed; means for drawing the leather into close relationship with said member; and means for bringing said knife blade into cutting relation with said leather.

30 16. In a machine for removing a portion of a piece of leather, a cutting member movable in a flat spiral path; a removable supporting member adapted to position the leather to be cut in the path of said knife, 35 said supporting member being provided with a supporting surface corresponding to the predetermined shape of the portion to be

removed by said cutting member; and means for moving said cutting member.

17. In a machine for removing a portion 40 of a piece of leather, a base; a frame pivotally supported on said base and means for locking it in a predetermined position; means for adjusting said frame axially in relation to its pivotal axis; a spindle journaled in said frame provided with a laterally extending arm; a cutter carrying member pivotally secured to said arm eccentrically to said spindle; a cutter mounted on said member; a cam track plate secured to 50 said frame having a face in a plane perpendicular to said spindle; a spiral cam track in said face; a finger on said cutter supporting member engaging said spiral cam track; means for rotating said spindle; a 55 removable leather supporting member positioned on said base directly under said spindle having a supporting surface of the predetermined shape of said portion to be removed; and means for securing said leather on said supporting surface.

18. In a machine for cutting leather, or like material, a support for said leather material of substantially a convex upper configuration, an operating spindle, a knife 65 operatively associated with said spindle, and means for causing said knife to move inwardly toward the axis of said spindle upon the operation of the spindle thereby to obtain a tapered cut of the material being 70 operated upon substantially as described.

Signed by me at Detroit, Michigan, U. S. A., this 8th day of April, 1924.

KARL L. HERRMANN.
